The ornamental design for a wheel or wheel cover, as shown and described.

(51) **LOC (9) Cl.** **12-16**

DESCRIPTION

(52) **U.S. Cl.** **D12/209**

This application contains subject matter related to the following pending U.S. patent applications:

(58) **Field of Classification Search** D12/204-213;

Application Ser. No. 29/350,139, filed Nov. 12, 2009 and entitled “Wheel or Wheel Cover”;

301/37.101, 64.101, 65, 64.201

Application Ser. No. 29/351,128, filed herewith and entitled “Wheel or Wheel Cover”; and

See application file for complete search history.

Application Ser. No. 29/351,130, filed herewith and entitled “Wheel or Wheel Cover”.

(56) **References Cited**

FIG. 1 is a front view of a first embodiment of a wheel or wheel cover according to my design; and

U.S. PATENT DOCUMENTS

FIG. 2 is a perspective view thereof.
